(57) CLAIM

The baby bottle, as shown and described.

DESCRIPTION

FIG. 1 is a top front perspective view of a baby bottle, showing my new design in condition for use;

FIG. 2 is a top front perspective view of the baby bottle of FIG. 1, shown in an alternate configuration for clarity of disclosure;

FIG. 3 is a front elevation view thereof;

FIG. 4 is a top plan view thereof;

FIG. 5 is a bottom plan view thereof;

FIG. 6 is a right elevation view thereof;

FIG. 7 is a left elevation view thereof; and,

FIG. 8 is a rear elevation view thereof.

The broken lines in the drawings depict portions of the baby bottle that form no part of the claimed design.

1 Claim, 3 Drawing Sheets
